Fairfield, Conn., assignors to General Electric Com-
pany, a corporation of New York

Application November 15, 1956, Serial No. 43,784

Term of patent 14 years

(Cl. D49—6)

Fig. 1 is a top plan view of a flatiron embodying this new design;

Fig. 2 is a side elevation showing this new design;

Fig. 3 is a perspective view looking downwardly toward the front portion of the flatiron with the cord bushing broken away for convenience of illustration only.

Fig. 4 is a perspective view looking downwardly toward the rear of the flatiron; and

Fig. 5 is a partial bottom view of the handle and temperature adjustment knob shown looking in the direction of arrow 5 in Fig. 2.

The dominant features of the design reside in the portions shown in full lines.

We claim:

The ornamental design for a flatiron, substantially as shown and described.
